UNITED STATES PATENT OFFICE.

JOHN THOMSON, OF BROOKLYN, NEW YORK.

WRENCH.

SPECIFICATION forming part of Letters Patent No. 256,867, dated April 25, 1882.

Application filed March 15, 1882. (No model.)

To all whom it may concern:

Be it known that I, JOHN THOMSON, of Brooklyn, county of Kings, and State of New York, have invented certain new and useful Improvements in Wrenches, which improvements are fully described and illustrated in the following specification and accompanying drawings.

My invention relates to screw-wrenches of that class commonly termed and known as "monkey-wrenches," in which the adjusting-screw is stationary and operates in a nut formed in the front of the sliding jaw; and my improvement consists in such a construction that the screw may be readily disengaged from the nut without changing the normal position of the hand while operating, whereby the adjustable jaw may be quickly changed from one position to another by the disengaged hand of the operator or the jaw be allowed to drop, as desired, by simply inclining the wrench, when the screw is again allowed to resume its position, either to lock the jaw or for use in ordinary manner.

In previous inventions relating hereto the uniform method of applying the disengaging mechanism is to the movable jaw. Thus the hand must follow the jaw in making adjustment or the position of the wrench be changed in the hand of the operator. It is the aim of my invention to obviate this objection, and, furthermore, to so apply the necessary means that no radical change shall be necessary in the regular manufacture of the class of wrenches described, and to add but little, if any, to the cost of the product.

In the accompanying drawings, Figure 1 is an upright side elevation of a common form of monkey-wrench, portions being shown as cut away to more clearly show my improvement. Fig. 2 is an upright cross-section on line 4 of Fig. 1, and Fig. 3 is a face view of a portion of shank with spring.

In Fig. 1, 5 is the ferrule, forming an end bearing for screw 6. 7 is the adjustable jaw, in which is formed the nut for screw. 8 is the shank, and 9 the rigid jaw.

The ordinary method of operation requires no description.

My device in its construction and operation is as follows:

The face of shank is first recessed, 10, Figs.

1 and 3, and a common tongue-spring, 11, is secured therein, its free end pressing outward against the screw in the grooved bearing 12. The inner semicircle of the thread forming the nut 13, nearest to the face of the shank, is next entirely cut away, as see 14, Fig. 2, and the end bearing 15 in ferrule, Fig. 1, slightly slotted in the direction of the shank. It will be seen that the tension of the spring 11 will hold the screw snugly to its bearing both in the segment of the nut and against the outer wall of the end bearing in the ferrule, and that the screw may be rotated by the milled head 16 adjusting the jaw 7—as if no alteration had been made—as in ordinary practice, and securing the jaw against thrust. Suppose it desirable, however, to make a quick and extreme change in the position of the movable jaw. Simply press sharply upon the milled head 16 with the thumb in the direction of the shank, as indicated by the arrow 17, when the screw will be forced inward upon the shank and detached from its bearing in the semicircular thread of the nut, thus leaving the jaw 7 free to be slid back or forth to any desired position upon the shank. Now relieve the pressure of the thumb upon the milled head and the spring will instantly force the screw back to its normal position, as shown in the figure.

The adjustment of the movable jaw may either be made by the disengaged hand or by simply inclining the wrench up or down, as the case may be. The jaw will gravitate to at least approximate the desired position upon the shank, when any further adjustment for close work may be effected by rotating the screw.

In the formation of the threads of the screw and nut that construction similar to a ratchet-tooth will readily suggest itself as being best adapted for the purpose herein described, the face of the thread receiving the thrust being at a right angle to the axis of the screw. A square or nearly square shaped thread, however, operates satisfactorily.

For economy of space the spring, as described, is let into the face of shank; but when secured thereto by a pin or screw, as 18, said spring may be attached to the face of shank without being recessed. The spring may be applied as shown in Fig. 3, in which the projecting heels 19 of the spring just fill the space between

the sides, but are a trifle less in thickness than the depth of the recess. The sides of the walls of the recess are then simply riveted over the spring, as shown, 20.

5 As will readily be apprehended, any form of spring will answer for the described purpose, although the style shown is considered preferable.

To recapitulate: The only changes necessary 10 to apply my invention in a wrench of the style shown and described are that the end bearing of screw be slotted or formed to permit a vibrating or lateral motion and the removal of a portion of the thread forming the nut, while 15 to the component parts but one is added—the spring 11.

What I claim is—

1. In an adjustable screw or monkey wrench 10 in which the movement of the sliding jaw is effected without changing the position of the hand during the rotation of the operating-screw, the combination of the semicircular nut, 20

as 13, screw, as 6, slotted end bearing, as 15, and spring, as 11, for the purpose of permitting the depression and detachment of said screw 25 from the movable jaw, whereby said jaw may be quickly slid or allowed to gravitate to any position on the shank, the screw being afterward used to lock the jaw, as in the ordinary manner.

2. In an adjustable screw or monkey wrench 30 in which the movement of the sliding jaw is effected without changing the position of the hand during the rotation of the operating-screw, the combination, with the rigid jaw, as 35 9, shank, as 8, sliding jaw, as 7, semicircular nut, as 13, screw, as 6, and slotted end bearing, as 15, of a spring, as 11, for the purpose specified.

JOHN THOMSON.
